UNITED STATES PATENT OFFICE.

MANNING E. WILSON, OF CANTON, PENNSYLVANIA.

RAILWAY-TIE.

1,199,850.

Specification of Letters Patent. Patented Oct. 3, 1916.

Application filed April 15, 1916. Serial No. 91,502.

To all whom it may concern:

Be it known that I, MANNING E. WILSON, a citizen of the United States, and a resident of Canton, in the county of Bradford and State of Pennsylvania, have invented an Improvement in Railway-Ties, of which the following is a specification.

My invention relates to railway road beds and particularly to ties for use therewith.

10 One object of the invention is to provide a tie, which will be cheap and easy to manufacture, extremely durable and possessed of the resiliency of the ordinary wood tie.

15 Another object of my invention is to provide a railway tie whose parts may be standardized and used interchangeably on roads carrying similar loads.

20 Another object is to provide a tie made in sections so as to admit of the removal of one portion without disturbing the other portion and so as to admit of the adjustment of one portion relatively to the other in such a manner that the tie may be used in road-beds of different widths.

25 The details of construction and arrangement of parts are shown in the accompanying figures of the drawing, in which—

Figure 1 is a plan view of the improved tie. Fig. 2 is a side elevation of the complete tie. Fig. 3 is an end view of the tie. Fig. 4 is a cross section taken on line a—a of Fig. 2.

The tie consists of two concrete or cement blocks 2 connected by iron rods extending longitudinally through them. Each block is formed of base, side, and end portions so as to leave a space within the block and open at the top thereof. The wooden block 1 which fills this space is molded in the block 2 when the concrete portion is formed. These concrete blocks may be and preferably are reinforced in any customary or well known way, but since the reinforcing does not form a part of my invention and in the interests of clearness I have not illustrated it. Each concrete block has a set of sleeves 3 extending longitudinally through the side walls and being of the same length as the blocks. The rods 4 pass through these sleeves making removal of the rods easy and effectively preventing any injury to the threads on the rods or to the blocks. The connecting rods are screw threaded at each end for a distance greater than the length of the blocks and each one carries a set of nuts all of

which may be moved so as to vary the distance between the blocks. When the blocks have been placed the proper distance apart, the nuts are screwed up tight against the blocks and thus hold them securely in place. 60

In practice the wood members embedded in the concrete blocks have their upper surfaces flush with or a trifle above the upper faces of the concrete blocks. The wood members 1 support the rails which are secured to them and furnish the necessary resiliency to absorb all shocks from the rails. By thus absorbing and cushioning the shocks before they are transmitted to the concrete members, the danger of breakage 70 of the concrete is minimized and the life of the block is greatly lengthened.

The sizes of the concrete and wood members are so proportioned that the concrete member is strong enough for all ordinary uses, 75 while the wood member has enough surface to permit the fastening of the rail thereto at several different points. This feature is of importance when the wood no longer affords a solid securing portion in one place but 80 does at another, for instance at an opposite end.

It will be apparent from the foregoing description and drawings that it will be easy to standardize all of the parts, thus making 85 cheap the cost of production of my tie. It is also obvious that the blocks may be used interchangeably since they are all alike.

In actual use, the possibility of removing one block without disturbing the other is 90 of considerable importance because of the saving in time and labor. Should one block break it could be replaced by a new block without disturbing the other block or the ballast around it. 95

While I have illustrated and described a preferred embodiment of my invention I do not wish to be limited thereby since various changes could be made without departing from the spirit of what is claimed. 100

Having described my invention what I desire to secure by Letters Patent is:

1. In an improved railway roadbed, concrete blocks arranged in pairs each block located transversely underneath and supporting a rail, the blocks consisting of a concrete shell open only at the top and carrying in the space so provided a wooden member to which the rail may be secured, said concrete block having molded therein 110

2
sleeves extending lengthwise of the block and through which rods joining the blocks may be passed substantially as described.

2. In an improved railway roadbed, rail 5 supporting members arranged in pairs and adjustably connected by screw threaded rods and nuts mounted thereon, sleeves molded in the longitudinal side walls of the said rail supporting members, to form casings 10 through which the screw threaded rods extend, substantially as described.

3. A railway tie comprising two reinforced concrete members each rectangular in longitudinal side elevations and square in trans-

verse end elevation, each concrete member 15 having molded therein a solid wooden block of greater length than breadth, the upper surface projecting slightly above the upper surface of the concrete member, each concrete member having molded in each side 20 portion thereof a plurality of mental sleeves which extend the entire length of the side portions for providing passageways through which rods connecting the two concrete members may be passed, substantially as de- 25 scribed.

March 20, 1916.

MANNING E. WILSON.
